UNITED STATES PATENT OFFICE

HERBERT M. FRIENDLY, OF PORTLAND, OREGON

TELEPHONE SYSTEM

Application filed June 18, 1923. Serial No. 646,119.

My invention relates to automatic or machine switching telephone systems, and variations thereof. It concerns the signaling current supply, switching mechanism and the 5 cross-connecting of the central office equipments with relation to the outside lines.

An object of the invention is to enable any desired character or harmonic frequency of signaling current to be applied through the 10 connector with specific reference to the line selected when the line is an individual line. Where the line selected is a party line it will have as many office branches as there are signals on the line. The latter statement is to 15 say there will be an office branch and corresponding telephone number for each station on the outside line, having in mind that there may be a plurality of central office branches for any desired station on the line; each said 20 branch having a distinctive telephone number and an interchangeable associated signaling current character or harmonic frequency. This provision of the invention enables any 25 desired type or character of signaling current and correspondingly responsive signal device to be employed for an individual line without changing its calling number. It also enables 30 any plurality of types or characters of signaling current and correspondingly selective 35 responsive signal devices to be employed on a party line without changing any calling numbers for any of the respective subscribers thereof. And it also enables any one or more 40 codes of signal current application to be made 45 to a line, selectively or non-selectively effective to a correspondingly responsive signal device or devices without changing any calling 50 numbers for any of the respective subscribers thereof.

55 A salient object of the system is the means whereby the subscriber grouping on party lines may be interchanged and altered without changing the calling numbers of the concerned subscribers wherein the type or character 60 of the signaling current and the signal device of the subscriber or subscribers concerned are or are not changed incidental to the changed grouping. That is to say, the present system contemplates broadly the interchanging or introduction of subscribers

on party lines as may suit the convenience of the operating concern from time to time, for engineering or other reasons without regard to the telephone number of the concerned subscribers or the character or code of signaling current to operate the respective subscriber's signal devices, with the exception, however, that no two subscribers would be assembled upon the same line signaled by the same current character and code application 65 thereof. This latter stated exception is to insure that a line will not contain a plurality of subscribers employing a like responsive signal device and code call, which condition would obviously cause confusion by reason 70 of both said subscribers being coincidentally signaled when only one or the other is wanted.

Another object of the invention is to enable a specific code of signaling current applications to be made over any branch and out upon the subscribers' line consequent to the branch being seized by the connector switch; the signaling current so projected being interchangeably specific to the said branch, but 75 applied through the said connector.

Another object of the invention is to provide a connector switch automatic control whereby when a branch of a line is seized which contemplates that code signals comprising a plurality of spaced applications of signaling current will be impressed, that the said applications will initiate only at the initial period of the code. That is to say, code current will not be applied initially 80 after the code period has begun, and which would thus cause fragmentary code signals to be applied out upon the line, possibly causing confusion with other codes employed upon the concerned line.

Another object of the invention is to insure that when continuously uniformly interrupted signaling current is applied to a seized line, the application of signaling current will initiate only at the beginning of the 85 live period so that fragmentary periods of application will not occur.

The present system relates in general to the system disclosed in my application Serial No. 154,790, filed March 14, 1917, issued as U. S. 100

Patent No. 1,565,727, granted December 15, 1925. The present system also relates to the system disclosed in my application Serial No. 138,149, filed December 21, 1916, and issued as U. S. Patent 1,561,710, granted November 17, 1925. It therefore, comprehends a system with the objects of the said filed applications as functions thereof.

The present system thus involves a cross-connecting means whereby any available signaling current supply may be interchangeably associated with the set of connector bank terminals corresponding to a line or branch of a line so that when the said set is seized by the connector the connector will receive the prearranged signaling current supply and impress it upon the talking terminals of the corresponding line or branch thereof seized. It also involves a cross-connecting means whereby the line may be interchangeably branched to any desired connector bank terminal set, or likewise branched to any plurality thereof in order that the line may be reached over any desired set of connector bank terminals, or over any set of any desired interchangeable plurality of connector bank terminal sets.

Referring to accompanying drawings:—

Fig. 1 shows a calling subscriber's automatic telephone T leading to a lineswitch LS. The lineswitch has access to a first selector FS. The selector FS has access to the connector A of the present invention.

Fig. 2 shows the wipers and one of the co-operating connector banks D for connector A, together with the wipers and cooperating connector banks B and C of two connectors (not shown) belonging to the group containing connector A.

Fig. 3 shows signaling current supply apparatus and signaling current interchanging terminals cooperative with a bank level of the group containing connector A and the multiplied connector bank levels B, C and D.

Fig. 4 shows the method of cross-connecting lines from the outside with relation to the sets of terminals E in Fig. 2 of the central office equipments.

The circuits employed to illustrate the invention may be assembled by placing Fig. 3 below Fig. 1, and Fig. 2 below Fig. 3 so that lines extending to the adjacent margins register.

With further reference to Fig. 1, the telephone T, lineswitch LS and first selector FS may be considered as A, C and E respectively, in the Patent No. 13,901 re-issued to Frank Newforth, Jr., April 13, 1915. The connector A is a well known form of connector switch as shown in Fig. 4 of the said Patent No. 1,565,727, however, modified to operate in accordance with the present invention. This modification is resident in the introduced right-hand relay and associated circuits, as will be discussed hereinafter.

In Fig. 3, the ringing current interrupter devices F, G, H, I, J and K are of the general type as the interrupter shown in Fig. 1 of the patent granted July 4, 1916, No. 1,189,882 to H. F. Obergfell. A group of these interrupters is common to a group of connectors of which connector A is one, but it will be understood that through the agency of contacts on relays L and M (relay M being commonly controlled from a group of connectors, only connector A of which is shown) certain or all of the interrupters may commonly serve an additional group or groups of connectors. In the present exemplified system, interrupter G is shown as controlled from either of the two groups to which relays L and M refer. When the connector A (or any connector of the group containing said A) seizes a line terminal set in its line terminal bank the common start conductor 101 will become extended through armatures 102 and 103 to grounded battery. This latter function, as will appear presently, will cause the relay L to actuate and the interrupter devices F, G, H, I, J and K to start functioning. As the brush 301 of interrupter F, for example, is drawn upward no operative effect occurs with reference to the signaling current source f, but the relay corresponding to 128 of any and every connector applying battery from its armature corresponding to 103 to common conductor 101 will be energized from battery on contact 307 over brush 301 and contact 308. Said relay (or relays) corresponding to 128 will be locked to common conductor 101 to close the conductor 218 of the concerned connector to the resting contact of its armature 136 to prepare for applying signaling current from source f through said armature 136 to the line seized by the connector. However, as the brush 301 recedes, following the breaking of the energizing path of the solenoid F in the manner set forth in the said cited patent to Obergfell, the five lower contacts at the left will be successively grounded through the brush 301, bar 302, spring 303, armature 304 to ground. This will cause relays as f' and f'' to successively operate to apply the source f through armature (or armatures) corresponding to 135 to the line called from the connector (or the respective connectors) having its relay corresponding to 128 locked, as will appear presently. It will appear presently that upon a response being obtained from a line called, the ring cut-off relay corresponding to 105 will actuate and lock in the well known manner, incidentally opening the grounded battery path from common start conductor 101, provided the latter said start conductor is not applied to grounded battery by some other connector of the group containing connector A. If the said conductor 101 is continued applied to grounded battery due to some other connector, the plunger-rod operating the brush 301 will continue reciprocating

in the manner as set forth in the said cited patent to Obergfell. The relay f' is connected to the fourth from the bottom contact 305, so when the brush 301 engages contact 305 in its downward stroke ground from armature 304 is applied through spring 303, bar 302, brush 301, contact 305 to the winding of relay f' , the latter said relay actuating and sustaining during the period brush 301 is passing over the said contact 305. The latter said period may be adjusted to any duration desired, and moreover, the relay f' may be given a slow-releasing characteristic to sustain the attracted armature on relay f' as long as desired.

A salient feature of the present invention is comprehended in the top-most set of contacts 307 and 308 adapted to be coincidently engaged by the brush 301 in the upward stroke. In this connection, it will be understood that the other contacts (310 for example), lead to relays as f'' corresponding to relay f' , respectively. The armature of relay f'' leads to a set of common interchanging terminals of a different connector bank level (not shown), connected correspondingly to the conductor 312 leading from the armature of relay f' . It will be understood that the conductor 312 and other correspondingly situated conductors of relays g', h', i', j' and k' may serve any plurality of connector bank levels and cooperating connectors. For example, if the installation consists of five-hundred connectors and respectively cooperating banks, the relays f' and f'' may each serve one-hundred connectors wherein the signaling current will be periodically applied to the respective groups successively in correspondence with the recession of the brush 301 over the contacts 305 and 310 in the manner set forth in the said patent to Obergfell. The up and down reciprocation of the brush 301 will continue as long as conductor 101 is applied to grounded battery by a connector of the group commonly related to conductor 101.

The signaling current sources f , g , h , i , j and k are preferably alternating current, though possibly pulsating current, for example. The sources f , g , h and i are currents having a definite frequency or periodicity for harmonically selectively operating line signal bells or other signal devices. The respective frequency of the said sources f , g , h and i may be conveniently assumed as 16, 33, 50 and 66 cycle. The sources j and k may be any said harmonic frequencies or they may be of any type of suitable signaling current, respectively. However, it will be noticed that while the relays f' , g' , h' and i' are similarly connected with relation to a single contact on their respective interrupter, the relays j' and k' are multiply connected to a plurality of contacts on their respective interrupter. In the case of relay j' it is con-

nected to two narrow contacts, with a wide contact interspersed between the narrow contacts. It will thus appear that as the brush 313 recedes, it will cause the relay j' to attract its armature briefly and then prolongedly and then briefly. This will cause a short, long and short application of source j to conductor 314. In the same manner, five short applications of source k will occur to conductor 315 for each recession of brush 317.

The ten sets of nine interchanging terminals correspond to the first to the tenth bank contact positions of the level shown in Fig. 2, which may be conveniently assumed to be the first off-normal level of the bank of possibly ten levels of bank terminals of connector A and associated group of connectors. The numerical designations (1 to 10) below the sets of terminals refer to the corresponding numerical position in the bank level concerned, there being a set of nine interchanging terminals for each connector bank position. It will appear presently that the signaling conductor, as 319 to 328, may be interchangeably connected with the armature of any relay f' , g' , h' , i' , j' and k' by electrically tying proper adjacent terminals of the set of terminals corresponding to the conductors 319 to the set of terminals corresponding to the conductors 319 to 328. This may be done by flexing the ends of the desired terminals into contact and applying solder thereto. It will be understood that any other method of interchangeably connecting the conductors 319 to 328 and the conductors leading to the armatures of relays f' , g' , h' , i' , j' and k' will answer the requirements of the present invention, such for example, as employing so-called jumpers.

In Fig. 4, the ten sets of terminals E at the extreme left are the correspondingly designated ten sets shown in Fig. 2, and are numerically designated 1 to 10 to index the corresponding bank position in the banks B, C and D to which they multiply connect. The said sets of terminals E are located on the intermediate distributing frame (designated I. D. F. in Fig. 4.), there being sets of cable conductors extending thereto from the corresponding sets of bank terminals shown in Fig. 2. The two sets of three terminals 401 and 402 are on a jumper branch block on the I. D. F. The vertical row of five sets of three terminals designated P are located on the I. D. F. From each set of terminals P a set of three cable conductors extend to a corresponding individual lineswitch indicated by a large circle. The two heavy lines leading to the lineswitches are talking conductors, while the light line is the so-called private normal conductor. That is, the said heavy lines correspond to conductors 123 and 124, and the said light line corresponds to conductor 50 of Fig. 1 of the cited patent to Newforth, having in mind that the type of

lineswitch employed is not limited to the general type shown (designated C) in the latter said patent.

The talking terminals of the respective sets of terminals P are connected by corresponding sets of two cable conductors to the arrester and heat-coil terminals designated Q. The terminal sets Q are located on the main distributing frame which is designated M. D. F. in Fig. 4. It is thus clear that the talking conductors leading to the lineswitches are commonly connected to talking terminals on the corresponding terminal sets P and Q on the I. D. F. and M. D. F., respectively, while the private normal conductor from the respective line switches terminate in a so-called "private" terminal on the I. D. F. companion to the terminals of the corresponding talking conductors leading from the respective lineswitches.

The outside subscriber lines respectively lead-in by cable as a pair of talking conductors and terminate in corresponding pairs of so-called line terminals on the M. D. F. in the well known manner.

The I. D. F. thus has a set of three terminals (two talking and one private normal) for each connector bank number in the central office, having in mind that each said number may be reached through a plurality of permanently multiplied bank terminals, possibly ten, three of which are shown in the levels designated B, C and D respectively, in Fig. 2. The set of terminals E thus shows terminals of ten connector bank lines belonging to a single level of ten line bank positions of a connector bank, which level, of course, may have any plurality of line bank positions (other than ten shown) per level and any plurality of levels; possibly ten levels. The I. D. F. also has a number of so-called branch blocks (as contain terminal sets 401 and 402) normally disassociated. The I. D. F. further has a set of three terminals (two talking and one private normal) for each lineswitch of the central office, having in mind there is a corresponding set of arrester and heat-coil terminals on the M. D. F. for each said lineswitch and its said terminals on the I. D. F.

The M. D. F. thus has a set of two talking so-called arrester terminals for each lineswitch of the central office, and a pair of talking so-called line terminals for and corresponding to each cable pair radiating from the central office for subscriber use. The M. D. F. may also contain line terminals for other uses; such as inter-office trunks, for example. However, the present invention is primarily directed to the means for interconnecting inside or office subscriber equipment to subscribers' lines, so auxiliary equipment elements are omitted in order to simplify the disclosure.

It will be noted here that the temporary

conductors or jumpers on the I. D. F. each constitute a set of three conductors, viz., two talking conductors and a private normal conductor. Also, that the jumpers on the M. D. F. each constitute two talking conductors only. It will, of course, be understood that while an I. D. F. and a M. D. F. have been referred to, a single cross-connecting frame may be employed embodying the elements described as located on the two said frames, and moreover, the method used in carrying out the objects attained by the present invention may be modified as to cabling, jumpering, and the relative disposition and organization of the temporarily and permanently associated elements without departing from the scope of the invention as defined by the appended claims.

The general organization of the elements of the system contemplated in the present invention having been set forth, detailed operation of the system in certain assumed calls will be described.

Assume a call from telephone T to telephone 405 (shown as a polarized telephone bell for simplicity) on individual line 1, the telephone number of which is "1112". Upon initiating the call (by removing the receiver) at telephone T, the lineswitch LS will operate and seize the first selector (assumed to be the first idle one accessible), the latter said selector being thereupon in condition to respond to the first digit "1" directly transmitted from the calling device 110. Upon the calling device 110 being operated, the selector FS will responsively operate and select connector A (assumed to be the first idle one accessible), in the well known manner, in view of the citation.

In this connection, it will be understood that in place of a single selector FS being intermediate of the lineswitch LS and connector A, there may be two or more selectors adapted to be interlinked in tandem, depending upon the numerical order capacity of the system. However, since employing a plurality of selectors as links in a tandem connection is not new in the art, the curtailed representation in Fig. 1 will be clearly understood as exemplary of the invention in its application to exchanges of all subscriber and numerical order capacities; the exemplified system having three numerical orders.

The connector A being well known in the art, so far as the directive control elements thereof are concerned, the operation of the line relay 112, release relay 113, series relay 114, vertical magnet VM, off-normal spring set ON, private magnet (designated Priv. M.), side switches 115 and 116, rotary magnet RM, busy relay 117, ringing relay 120, ring cut-off relay 105, back-bridge relay 122, release magnet (designated Rel. M.), will be fully understood, and therefore need not

be detailed. Suffice it to say, however, that upon the shaft of connector A being operated responsive to the last two digits "12" of the called number, its wipers 211 to 214 in Fig. 5 will become set upon the second set of bank contacts of the bank level D. Assuming the said called line to be idle, the relay 120 will actuate in the well known manner, and ground will be applied through sideswitch wiper 116, conductor 124, wiper 211, engaged bank contact, conductor 216, I. D. F. terminal 217, conductor of jumper 406, I. D. F. terminal 407, private normal cable conductor leading to the cut-off relay of the lineswitch 10 408. This will be effective to the said lineswitch to disconnect or cut-off the line relay thereof from the talking conductors leading thereto, in the well known manner.

Consequent to the said actuation of relay 120, a circuit path can be traced from grounded battery, armatures 103, 102, conductor 101 and through the winding of relay L to ground, the latter said relay actuating. A circuit path can now be traced from grounded 25 armature 304 to the multiplied windings of the solenoids of the interrupter devices F, H, I, J and K. A circuit can also be traced from grounded armature 330 to the winding of the solenoid of interrupter G. The said interrupters will be thus caused to start operating in the manner explained in relation to interrupter F.

It will be noted that the second and third (from the top) interchanging terminals of 25 the second set (from the left) are electrically tied (by soldering, for example) so that a circuit path can be traced from contact 331, armature of relay g', common conductor 332, tie 333, conductor 320, bank contact and wiper 212, conductor 218, make-before-break spring 40 126, winding of relay 128, armatures 129 and 130 to ground. The relay 128 is designed (through the employment of a core shield or otherwise) to have the characteristic of 45 relay 105 wherein it will operate from sustained direct current, but will be nonoperative to alternating current, or to brief applications of current or to inductive currents.

The contact 337 being normally disengaged, 50 the energization of the traced path including the winding of relay 128 will not occur until brush 335 is raised to coincidently engage contacts 331 and 336, at which time the grounded battery source attached to contact 336 will operatively energize the relay 128 over the traced path. A locking path for relay 128 can now be traced from spring 126, armatures 131, 102, 103 to grounded battery, the contact upon which spring 126 normally 55 rests being now disengaged. The lower pin 337 on the plunger-rod carrying brush 335 striking spring 338 will disengage the spring upon which spring 338 normally rests and the latter spring engages the spring shown above, so that the ground from armature 330 will

now be applied to the bar 339 and the energizing path for the solenoid of interrupter G will be broken so that the brush 335 will start receding; its left-hand end successively engaging the contacts while the right-hand end slidingly engages the bar 339. At the time brush 335 engages contact 340, relay g' will become energized in the manner as has been stated with reference to relay f'. During the time relay g' is actuated, ringing current from source g will be applied through armature of relay g', conductor 332, tie 333, conductor 320, bank contact and brush 212, conductor 218, armatures 135, 136, 137, conductor 140, wiper 213 and engaged bank contact, terminal 220, talking conductor of jumper 406, terminal 410, cable conductor 412, arrester terminal 413, lower conductor of line 1, condenser and bell 405, upper line conductor, terminal 417, corresponding conductor of jumper 415, arrester terminal 419, cable conductor 420, terminal 421, corresponding conductor of jumper 406, terminal 223, armatures 142, 143, inner winding of relay 105 to grounded battery. The bell 405 being responsive to the current from source g will operate, while the relay 105 will not operatively energize. The interrupter device G will continue to reciprocate its brush 335 as long as conductor 101 remains applied to grounded battery, an application of the source g over the traced path including bell 405 occurring each time the brush 335 engages contact 340 during its recession, but not during its attraction, because of bar 339 being dead under the attracting condition as spring 338 is then resting as shown in the drawing. 70 75 80 85 90 95 100 105 110 115 120 125 130

In this connection, attention is directed to the fact that if relay 120 in connector A actuates after brush 335 has left bank contact 331 in receding (common conductor 101 having been before applied to grounded battery by some other connector of the group containing connector A) the actuation of relay g' will have no operative effect on the bell 405, due to relay 128 being normal, though relay g' may apply current from source g to another bell through a connector of its group having operatively seized a line before brush 335 left contact 331 in its downward stroke in the manner described. Under the last stated condition, signaling current from source g will find its way over the traced path including the winding of relay 128 to grounded armature 130, but due to the stated characteristic of relay 128 it will not operatively respond to the signaling current source g, or other signaling current source, such as f, h, i, j and k. The resistance of relay 128 is preferably high, so that it will not abstract an objectionable drain of signaling current from the applied source, and moreover, the ground path from armature 130 may include a retardation coil (not shown) common to all the connectors of the group containing connector 135

A to further bar or suppress the signaling current from the source being applied.

Upon a response being obtained on the called line by the removal of the receiver from the switch-hook of the telephone indicated by bell 405, a conductive path will be closed including grounded signaling current source and the inner winding of relay 105, causing it (relay 105) to actuate and lock its outer winding through armature 145 to grounded lower off-normal spring, incidentally grounding the upper terminal of the lower winding of back-bridge relay 122. Relay 122 will actuate in the well known manner and armature 103 will remove grounded battery from conductor 101, having in mind conductor 101 may remain applied to battery from some other connector armature corresponding to 103. Due to the armature 130 attracting, the relay 128 will become unlocked, regardless of the state of conductor 101. The relay 122 will operatively energize through armatures 136 and 143 and the traced path including the receiver of telephone on line 1. The calling and called telephones are now in talking connection. The restoration of the connector concerns well known circuit paths and elements and therefore need not be detailed in imparting a clear disclosure.

Assume that in the described call the tie 333 is transferred or interchanged to the fourth and fifth terminals in lieu of the second and third as shown. The source *h* will be applied by relay *h'* in lieu of source *g* by relay *g'*. In the present assumed case, the bell 405 will require changing, provided it was selectively responsive to the source *g*, though if non-harmonic, it may be universally responsive to the signal current, and therefore responsive to the current from source *h*.

Assume that the tie 333 is interchanged to between the two terminals lowermost, in lieu of the second and third, as shown in the drawing. The source *k* will be applied by relay *k'* in lieu of source *g* by relay *g'*. In this connection, it will be noted that while the topmost left-hand terminal 341 engageable to brush 317 leads to the resting contact of the armature of relay *k'* and the corresponding right-hand contact 342 leads to grounded battery, simulating the arrangement of the interrupter *G*, the winding of relay *k'* is multiplied to the five contacts consecutively below contact 341. Thus, as the brush 317 recedes after its lower pin 343 engages and operates the spring 344, the ground from armature 304 will be applied through spring 344, bar 346, brush 317 to the successively engaged contacts below contact 341, effective to vibrate the armature of relay *k'* five times, thereby correspondingly applying and disconnecting the signal current source *k* with respect to conductor 315, the present assumed tie, conductor 320 and over the before traced path to

ground at armature 130 if it is assumed that the concerned connector relay 120 actuated after brush 317 receded from contacts 341 and 342. However, the relay 128 will not be operatively affected by the said current, due to its stated design. Upon the brush 317 being next moved into engagement with contacts 341 and 342, the grounded battery at contact 342 will be applied through the armature of relay *k'* and over the traced path including the winding of relay 128 to grounded armature 130, causing relay 128 to actuate and lock, as described. This will prepare the signaling circuit at armature 135, so when the receding brush 317 successively grounds the contacts attached to the winding of relay *k'*, five applications of signaling current will be successively impressed over the described path including the bell 405. If it is further assumed that the bell 405 is responsive to the current from source *k*, a code of five "bells", so-called, will ensue. It is thus clear that since the brush 317 must engage contacts 341 and 342, in order to close the signaling circuit at armature 135, it will be impossible to initiate the application of code signaling current from any connector at any period other than the initial period of the code. And it will also be clear that regardless of the number of connectors similarly related for signaling with reference to the interrupter device, the respective connectors will remain disabled from applying signaling current until the first engagement of brush 317 with contacts 341 and 342 after the seizure of the concerned connector by the actuation of its relay corresponding to relay 120 to complete the ground path from the lower winding terminal of the relay therein corresponding to relay 128. The removal of grounded battery from conductor 101 by the attraction of armature 103 will de-energize relay *L*, consequent to the response on the called line, as before described, having in mind that conductor 101 may be maintained to grounded battery by another connector in seized relation which has not been responded to from its called line, though the conductor 218 will not now lead to an operative path due to armatures 130 and 136 being attracted during the responded state of the called line.

Assume that the tie 333 is interchanged to the seventh and eighth terminals in lieu of the second and third, as shown. The source *j* will become related to conductor 320 as was source *k* in the last assumed description. The relay *j'* has the same disposition and function with relation to the interrupter *J* as relay *k'* has to interrupter *K*, having in mind that the contact 348 covers the space of three spaced contacts of interrupter *K*. Thus, as the brush 313 recedes, the relay *j'* will be caused to attract its armature for a relatively long period intermediate of two short attracted periods. This will effect a code signal constituted of a

short, long and short "bell" to the called line. The function and object of the contacts 352 and 353 correspond to that of the contacts 341 and 342.

5 It is thought that the foregoing makes clear the functioning of the connectors and the interrupter devices shown, having in mind there may be any desired plurality of signaling current sources or codes; six only being shown for the purpose of illustration.

10 The employment of the devices of the system wherein party lines are concerned will be discussed. The party lines may have the respective stations thereon signaled selectively harmonically or alternatively by code, or 15 the signaling may be both harmonic and code, as will appear.

Line 2 has two harmonic signal devices 421 and 422 as a part of the concerned telephones (not detailed), selectively responsive to 20 16 cycles and 50 cycles, respectively. It will be noted that a jumper 425 is run corresponding to jumper 415. Since the outside cable conductors and the main frame elements are adapted to universal use; that is, 25 may be employed in individual line or in party line service they will be similarly jumpered on the M. D. F. under either use. However, the line 2 is a party line, having two selectively signaled subscribers stations thereon, and the fact that the station thereon designated 421 is reached by calling telephone number "1115" wherein 16-cycle signaling current is impressed from source *f* and the 30 station designated 422 is reached by calling telephone number "1117" wherein 50-cycle signaling current is impressed from source *h*. In order that the signaling characteristic of each of the telephone signals 421 and 422, 35 and also the calling numbers of the said telephones may be singly or both changed (in regrouping, for example) without disturbing the two-conductor jumper 425 and the unconcerned three-conductor other jumper, a 40 branch-block terminal set 401 is arbitrarily chosen to which to run the three-conductor jumper 427. The branch-block 401 may have its three terminals arranged in multiplied gangs respectively, wherein when corresponding sets of lugs of the terminals are 45 distinctively set apart for each current character it enables the junctioned jumpers from the connector bank terminal sets to be attached thereto to be identified with respect 50 to the subscriber's stations to which each jumper refers. However, the latter referred to convenience is a detailed feature. It will now be clear that when jumpers 429 and 430 are run to the fifth and seventh sets of terminals of the level group E, the line 2 may 55 be reached by setting the wipers 211 to 214 of connector A upon either the fifth or the seventh set of bank contacts of the bank level group D; or the line 2 may be reached from 60 the corresponding positioned bank contact

sets in level groups B and C, as well as from other multiplied level groups thereof, not shown. Also, it will be clear that the placing of the tie on each the fifth and seventh set of interchanging terminals shown in Fig. 3 70 will determine what specific source of signaling current will be impressed by the connector when seizing the line 2 from either of its said two branches.

The drawings show the first and second terminals of the fifth set of the signaling current terminals tied by tie 355, and the fifth and sixth set of the seventh set tied by tie 356. Thus, when a connector seizes the fifth set of bank terminals, 16-cycle current from source *f* will be impressed upon the line 2, and when a connector seizes the seventh set of bank terminals 50-cycle current from source *h* will be impressed upon the line 2. From what has been described, it is clear 85 that changing either or both the ties 355 and 356, will enable the source to be impressed to the line 2 over the jumper branches 429 and 430 to be changed at will, having in mind that the bells or signal devices on the line 2 will 90 be changed to be responsive to the applied source. Further, the jumpers 429 and 430 may be independently changed from one set of bank terminals of the connector bank group to another or to any other bank group 95 (not shown) of the central office. The latter would be done if a change or re-grouping of subscribers were desired; the jumpers being run to the connector bank numbers corresponding to the telephone numbers of the 100 subscribers connected on the line. Of course, the bells 421 and 422 will be differently selectively responsive to avoid confusion, but there is no definite signaling current character attached to the subscriber number, so 105 the signaling current character (and the bell) may be changed as and when desired, by altering either or both ties 355 and 356 as has been referred to.

Assume that it is desired to substitute the subscriber having telephone number "1118" for the one having telephone number "1115", the latter subscriber discontinuing his service, or perhaps being grouped with subscribers on some other line. The jumper 429 will be transferred to the corresponding terminals of the eighth set of the level group E and the bell 421 displaced by a bell responsive to any available source other than 50-cycle employed to operate bell 422. Assume this chosen bell is responsive to 66 cycle current, perhaps because the subscriber's bell formerly responded to this signaling current frequency, and therefore employing the same bell will obviate 110 changing his telephone. In this event a tie 358 will be made between the fifth and sixth interchanging terminals of the eighth set, connecting conductor 326 to the armature of relay *i'*, wherein the latter said relay is oper- 115 120 125 130

ated by interrupter I in the manner made clear in foregoing descriptions.

The subscriber's telephone 421 disconnected from the line 2, the telephone number of which is "1115", may now be attached to any suitable outside line having a subscriber vacancy. A jumper will be run from the fifth set of terminals of level group E (being connector bank number "1115" belonging permanently to the concerned subscriber) to the branch-block corresponding to 401 or 402, for example, associated with the line to which the telephone 421 is transferred. In this connection it will be noted that if the line to which the latter said telephone 421 is transferred has no signal current (16-cycle) associated therewith to cause confusion, no change further than the said running of the frame jumper (retaining tie 355) will be necessary after changing the telephone from line 2 to the new line. But if the new line already has a signal device (and code) which is like that of the changed telephone 421, any signal current (or code) different from those used will be chosen, and the tie 355 changed accordingly, which completes the re-grouping, having in mind that the signal device of the telephone will have to be changed to correspond to the impressed signaling current, in case the tie 355 is not retained as shown in the drawing. It will be understood that in case the telephone 421 is to be on an individual line, the new jumper run from the fifth set of terminals of the group E will be run to a vacant set of terminals as 468, for example, and a second jumper will be run from terminals 467 to a set of outside line terminals of the group containing the terminals of lines 1 to 4, but not shown, upon which the said individual line terminates. Under the latter assumed condition incoming calls will be extended through the lineswitch 465, while outgoing calls will be extended over the jumper attached to the said fifth set of terminals of the group E, as when the telephone 421 was on the line 2.

The bells 421 and 422 on line 2 are operated by 16-cycle and 50-cycle current, respectively. If it is assumed that a subscriber having telephone number "1118" be connected to said line 2 and that the bell therefor will be responsive to 50-cycle code of five "bells", a jumper will be run from the eighth set of the group E to the branch block 401, its conductors correspondingly attaching. The tie 358 in Fig. 2 will not exist and a tie will be placed between the lower two terminals of the eighth group in Fig. 3. This will connect conductor 315 to conductor 326 so that when the eighth set of bank contacts are seized by wiper set 211 to 214 (or any other set of wipers having access to a multipled bank contact set thereof), the line 2 will be signaled upon from the source *k* whereby a code of five "bells" will occur to the newly added telephone (not

shown) and also to the bell 422. The subscriber having bell 422 will ignore the five "bells" while the newly added subscriber will respond wherein the concerned connector will function as has been set forth upon a response occurring. Regardless of the position of brush 317 when the connector seizes the line 2 the signaling current from the seizing connector will not be initiated until brush 317 has encountered contacts 341 and 344 and has receded to the first successive contact in the manner as has been set forth in descriptions with relation to connector A. When the line is seized by a connector over the branch including the jumper 430 wherein the source *h* will be applied to the connector through the tie 356 the bell 422 and the bell of said newly added telephone will operate, but as codes of one "bell" will be now applied by the seizing connector the newly connected subscriber will ignore the signal. It will be manifest in view of the descriptions, that in lieu of tying the lower two terminals of the eighth set in Fig. 3, the seventh and eighth terminals thereof may be tied so in that event a short-long-short code of 33 cycles will be applied from source *j* by the connector seizing bank "1118". In this case, no bell on line 2 would respond, unless the bell of the newly added telephone were made responsive to 33 cycle current, which, of course, would have to be done to establish the said new subscriber in service.

Any of the subscribers on the line 2 upon initiating a call will cause the associated lineswitch 435 to function and extend the call to a first selector as in the case of the call initiated from telephone T. The private normal conductor will then apply ground to the private normal conductor of the jumper 427 and over the private normal conductors of the jumpers (as 429 and 430) branching from the branch-block terminal set 401 to the connector banks corresponding to the associated telephone numbers to guard the line against intrusion by a connector over any of its central office branches. As the private normal conductors of the central office branches of the line 2 are mutually tied, when any said branch is seized by a connector, all the branches are simultaneously guarded against intrusion by a connector, as well as operating the lineswitch cut-off relay.

The branch-block 402 serves to junction the corresponding conductors of jumpers 441 to 444, which lead from the first, third, sixth and tenth set of terminals of connector bank group E, respectively, so the line 3 may be reached over the said branches and jumpers 445 and 446 by calling telephone numbers "1111", "1113", "1116" and "1110", respectively. The line 3 has telephone bells 451 to 454 thereon selectively responsive to 16-cycle, 50-cycle, 33-cycle and 66-cycle signaling current, respectively. Due to ties 361 to 364 corresponding to the jumpers 441 to 444, the sources *f*, *g*, *h*

and *i* will be applied selectively effective to the bells 451 to 454 when any of telephone numbers "1111", "1113", "1116" and "1110" is called, respectively.

The disposition of the lineswitch 461 with respect to line 3 and accessible first selectors and the connector bank branches reached over jumpers 441 and 444 corresponds to the relationship of lineswitch 435, line 2 and its connector bank branches reached over jumpers 429 and 430. It will be clear that the responsive characteristics of the bells on line 3 may be changed without service confusion by correspondingly altering the ties on the concerned interchanging set corresponding to the concerned telephone number; furthermore, that any or all of the jumpers 441 to 444 may be changed to be connected over responsive to the calling party calling any desired telephone number, having in mind that the interchanging terminals (corresponding to those in Fig. 3) will be tied to adapt the connector seizing any said line branch to apply signaling current to selectively operate or code the corresponding telephone bell on the outside line. It will be clear, for example, that changing the tie 361 to tie the ninth and tenth terminals in lieu of the first and second, will adapt a connector seizing the first set of bank contacts of the level (responsive to calling telephone number "1111") to project a code of five "bells" of 50-cycle current over the jumper 441, effective to bell 453 in lieu of one "bell" of 16-cycles.

In view of foregoing descriptions, it will be manifest that if it is desired to change the telephone represented by bell 452 from the line 3 to the line 2, all that will be required is to change the connection of the telephone from the one to the other said line and transfer jumper 443 from the branch terminal set 402 to corresponding lugs on the branch terminal set 401. A new telephone, the bell of which is not responsive to any of the employed cycles on line 3 may be connected thereon to replace the line vacancy made by the transferring of the telephone represented by bell 452, and a jumper like 443 run from branch-block 402 to the connector bank number corresponding to the calling number of the added telephone. It will, of course, be understood that the said new telephone may be responsive to current cycles employed to selectively signal the other subscribers or a subscriber on the line 3, but in each event a new code from that then employed on line 3 will necessarily be chosen for the newly added telephone to forestall confusion. Two of the signaling current interchanging terminals of the connector bank number of the said new telephone will be tied to adapt any connector seizing the line 3 through the latter said connector bank number to project signaling current from the proper source to selectively signal the subscriber corresponding.

The lineswitch 465 is dead, being cabled to arrester 467, the cable sets to the lineswitch 465 and to the arrester 467 having the talking conductors tied multiply at the terminal set 468.

The line 4 has telephone bells 471 and 472 responsive to 33 and 50 cycles, respectively. The line 4 is connected over jumper 470 to an arrester and corresponding lineswitch 471 on the M. D. F. Jumper branches 473 and 474 from the lineswitch terminals on the M. D. F. lead to the fourth and ninth terminal sets of level group E. These jumpers 473 and 474 therefore correspond to telephone numbers "1114" and "1119", respectively. Due to the placing of the ties 371 and 372, the seizing connector will be adapted to project current from source *j* if the branch including jumper 473 is seized whereby the bell 471 will be operated, and the seizing connector will be adapted to project current from source *k* if the branch including jumper 474 is seized whereby bell 472 will be operated. In the case of applying source *j*, a code consisting of a short-long-short series of "bells" will ensue; each code always being initiated at its beginning in the manner as has been explained. In a comprehensive, commercial system there would ordinarily be a greater number of code combinations than shown, but the method of applying them alternatively to any line will be as has been set forth. In instances, all of the sources may be code, consisting of a plurality of "bells" for a signal.

It will be manifest that the tie 372 may be changed from the eighth and ninth terminals to any other adjacent ones by correspondingly changing the bell 472 to be responsive to the changed signal current source associated with the branch including jumper 474. However, if the said tie is changed to the third and fourth terminals, 50-cycle current will be then adapted to be projected from source *h* through a connector seizing the branch including jumper 474, so the bell 472 will be operative to the periodic non-code applications.

The jumpers 473 and 474 run directly to the terminals of lineswitch 471, in lieu of through branch terminal set of the type of 401, for example, thus obviating the employment of a jumper corresponding to 427, for example, though it will be clear such an intermediate branch terminal set may be employed if desired, since the system admits of variation without departing from the scope of the invention.

In commercial operation, certain divisions of the arrester terminals on the M. D. F. may be set aside for lines of the different classifications. This will mean that the lineswitch terminals on the I. D. F. will be correspondingly segregated. It will thus be found convenient (and in fact, it is contemplated in the present invention) to use gang-terminals for

the lineswitches reserved for the different plurality classes of party lines, so that the jumpers from the connector bank terminals may junction at the I. D. F. lineswitch terminal set concerned. This, for example, will 5 obviate the jumper as 445 and the branch terminal set 402, since the jumpers 441 to 444 would all run directly to the gang-terminals of the lineswitch 461. The jumpers 473 and 474 are run in the manner last set forth. 10 There would not necessarily be any segregation as to classes in the connector banks. On the other hand, the diversifying of the classifications in the connector banks promotes making the coincident traffic uniform in the 15 various groups at all times of the day, as the traffic characteristics of the diverse classifications constituting the groups will intermesh. The more uniformly the groups are diversified as to classification of the subscribers 20 reached therethrough, the more uniform will be the coincident traffic in the connector groups of the central office, thus requiring the minimum of connectors for a stated traffic for 25 the central office. The present invention lends itself as one of its objects, to promote the said diversifying of the traffic among the connectors of the central office.

The illustrative cross-connections have concerned a single level of a connector bank group, but it will be understood that this method has been used as it appeared the simplest manner of disclosing the comprehensive system contemplated, and its operation. The 30 system contemplates that each level of a plurality of multi-level (or single level) bank groups will be arranged as shown in Figs. 2 and 3 wherein all the bank groups terminate on the I. D. F. for cross-connection with the conductors of any level or levels of the said 35 plurality and with the desired subscriber's line, wherein interchangeable central office branches from a subscriber's line may terminate into widely separated connector bank groups not having designed permanent relation.

It will appear, in view of the foregoing descriptions, that I have provided, among other functions, a system of assembling central office equipment elements of well known 40 type and also of equipment elements of the present invention, with outside subscribers' lines wherein changes of groupings of party subscribers may be made without changing 45 calling numbers of the concerned subscribers, regardless of the type and kind of signaling current it is found convenient to employ from time to time for the bells, with due regard to selective calling. The invention also provides 50 for keeping party lines filled to operating capacity, because in the event of disconnecting a telephone, a new telephone having any desired telephone number, may replace it. Moreover, the said added telephone may be 55 responsive to any available signaling char-

acteristic, and then changed from time to time without changing the calling number.

The system of the present invention thus lends itself to re-grouping subscriber lines from time to time to conform to the most economical treatment of the outside plant as 60 regards party line grouping. It also conduces to the employment of the lineswitches to their fullest party capacity, because when a disconnection of service is made with reference to any party line, the connector bank branch or number concerned, and not any fraction of the lineswitch capacity of the central office, is the only portion of the central office equipment taken out of earning service until the disconnected subscriber's number is omitted from the subscriber directory. This also applies when an individual subscriber changes to a party line classification 65 or when he discontinues his service. In the case of disconnecting the service, the connector bank number is the only element of the central office equipment retained out of revenue service, and the latter is only so retained until the disconnected subscriber's number is omitted from the subscriber directory. The said connector bank number or branch represents a relatively small capital 70 investment as compared to the lineswitch capacity which would be lost were not some method, such as is provided in the present system, provided to reinstate the lineswitch idleness forthwith after such idleness occurs; whether the idleness is occasioned by the disconnection of an individual line therefrom or 75 one of a plurality of party subscribers from a connected party line.

The system of the present invention thus permits a connector to receive and impress only a specific one of various adaptable signaling current characters or codes upon any of a plurality of accessible called subscriber lines or branches of such consequent upon seizing the called line or branch without the necessity of the calling subscriber performing a specific signaling current selecting operation. Seizing the called line or branch of the called line determines the character of the code of signaling current to be applied directly from the connector wherein but one character of signaling current is then present in the connector. And, moreover, that the said one character of current present in the connector cannot be applied from the connector excepting at a predetermined time of the operativeness of the current or code. That is, the character and code of the signaling current received and impressed by the connector is determined by and merely incidental to the selective setting of the connector with respect to connecting with the terminals of the called line.

Again, the system operates to obviate number changing when re-grouping party subscribers, and where changing the type of sig-

naling current or the code thereof is desired for any reason. Changing numbers is annoying to the subscribers and the records of such may become a large item of expense to the 5 operating concern in currently maintaining same and in giving this information to its subscribers when calling changed numbers. The latter is aside from the idle traffic created by calling subscribers to obtain changed number information and the annoyance occasioned to the calling subscribers in obtaining the change information.

I claim:—

1. In a telephone system, a connector 15 switch, line bank contacts for the connector, signaling contacts for the connector bank corresponding to the line contacts, a plurality of sources of different signaling currents, line and signaling wipers for the connector, a connecting rack for interchangeably connecting said sources of signaling current and the bank signaling contacts, a connection extending from the signaling wiper to a line wiper for conducting signaling current from the selected bank signaling contact to 25 said line wiper, telephone lines, and a second connecting rack for interchangeably connecting said lines and line contacts.

2. In a telephone system, a connector 30 switch, line bank contacts for the connector, signaling contacts for the connector bank corresponding to the line contacts, a plurality of sources of different signaling currents, line and signaling wipers for the connector, a connecting rack for interchangeably connecting said sources of signaling current and the bank signaling contacts, a connection extending from the signaling wiper to a line wiper for conducting signaling current from the selected bank signaling contact to 35 said line wiper, signaling current interrupter means included in the signaling current path, telephone lines, and a second connecting rack for interchangeably connecting said lines and line contacts.

3. In a telephone system, a connector 40 switch, line bank contacts for the connector, signaling contacts for the connector bank corresponding to the line contacts, a plurality of sources of different signaling currents, line and signaling wipers for the connector, a connecting rack for interchangeably connecting said sources of signaling current and the bank signaling contacts, a connection extending from the signaling wiper to a line wiper for conducting signaling current from the selected bank signaling contact to 45 said line wiper, a signaling current interrupter interposed between the sources of signaling current and the first said connecting rack, telephone lines, and a second connecting rack for interchangeably connecting said lines and line contacts.

4. In a telephone system, connector 50 switches having multiply connected bank line-

contacts, party telephone lines having selective signaling devices connected thereto, a connecting rack for interchangeably connecting a party line to a plurality of desired bank contacts of the connector switches, sources of 55 signaling current corresponding to the line terminals, bank signaling contacts on the connector switches corresponding to the bank line contacts, and means for interchangeably connecting the sources of signaling current to the bank signaling contacts to correspond with the selective signals on any line.

5. In a telephone system, groups of connector switches each group having multiply connected bank line-contacts, party telephone 60 lines having interchangeable selective signaling devices connected thereto, means for interchangeably connecting a party line to a plurality of connector contacts of the same or different groups, sources of signaling current corresponding to the selective signals, bank signaling contacts on the connector switches corresponding to the line contacts, and means for interchangeably connecting the sources of signaling current to the signaling contacts to correspond with the selective signals on any line.

6. In a telephone system, groups of connector switches each group having multiply connected bank line-contacts, party telephone 65 lines having interchangeable selective signaling devices connected thereto, means for interchangeably connecting a party line to a plurality of connector contacts of the same or different groups, sources of signaling current corresponding to the selective signals, bank signaling contacts on the connector switches equal in number to the line contacts and corresponding thereto, and means for interchangeably connecting the sources of signaling current to the signaling contacts to correspond with the selective signals on any line.

7. In a telephone system, a plurality of party-telephone lines, a plurality of connector switches having bank line-contacts, means for interchangeably connecting said lines and a number of contacts on the connector switches corresponding to the number of telephones on a line and independent of any predetermined numerical relation of the contacts, sources of signaling current corresponding to the telephones on the party lines, signaling current bank-contacts corresponding to the line-contacts, and means for interchangeably connecting the sources of signaling current and signaling contacts according to the telephones connected to the lines.

8. In a telephone system, groups of connector switches each group having multiply connected bank line-contacts, party telephone lines having interchangeable selective signaling devices connected thereto, means for interchangeably connecting a party line to a plurality of connector contacts of the same or

different groups, sources of signaling current corresponding to the selective signals, signaling current bank-contacts equal in number to the line contacts and corresponding thereto, and means for interchangeably connecting the sources of signaling current to the signaling contacts to correspond with the selective signals on any line.

9. In a telephone system, groups of connector switches each group having multiply connected bank line-contacts, party telephone lines having interchangeable selective signaling devices connected thereto, signaling current bank contacts equal in number to the line contacts and corresponding thereto, means for interchangeably connecting a party line to a plurality of connector contacts of the same or different groups, sources of signaling current corresponding to the selective signals, and means for interchangeably connecting the sources of signaling current to the signaling contacts to correspond with the selective signals on any line.

10. In a telephone system, a connector switch having sets of bank contacts each including a line contact and a corresponding signaling contact, line and signaling wipers for the connector, a plurality of sources of different signaling currents, a connecting rack for interchangeably connecting said sources of signaling currents and the bank signaling contacts, telephone lines each having one or more telephones and interchangeable signal devices corresponding to the different signaling currents, a second connecting rack for interchangeably connecting said lines and one or more sets of the line contacts indiscriminately, whereby said telephones may be changed from one line to any other without changing their calling numbers.

11. In a telephone system, groups of connector switches each group having multiply connected bank line contacts, party telephone lines having interchangeable selective signaling devices connected thereto, means for interchangeably connecting a party line to a plurality of connector contacts of the same or different groups, sources of signaling current corresponding to the selective signals, means controlled depending upon the bank line contact seized in attaining connection with the line for adapting a predetermined one of said sources of signaling current to be projected over the line, and means for interchangeably connecting the sources of signaling current to correspond with the bank line contacts and the corresponding selective signals on any line.

12. In a telephone system, a plurality of party telephone lines, a plurality of connector switches having bank line contacts, means for interchangeably connecting said lines and a number of contacts on the connector switches corresponding to the number of telephones on a line and independent of any predetermined

numerical relation of the contacts, sources of signaling current corresponding to the telephones on the party lines, means controlled depending upon the bank line contact seized in attaining connection with the line for adapting a predetermined one of said sources of signaling current to be projected over the line, and means for interchangeably connecting the sources of signaling current to correspond with the bank line contacts and the corresponding selective signals on any line.

13. In a telephone system a line, a connector switch, line bank terminals for the connector, branches of the line extending to a plurality of the said terminals, a plurality of sources of signaling current, means for impressing a said source of signaling current upon the line for operating a selective signal device thereon dependent upon what line branch bank terminal is seized by the connector, a connecting rack for interchangeably connecting said sources of signaling current, and means for interchangeably connecting the said branches to correspond with the related signaling current sources and the said signal devices on the line.

14. In a telephone system, a connector switch, line bank contacts for the connector, signaling contacts for the connector bank corresponding to the line contacts, a plurality of sources of different signaling currents, line and signaling wipers for the connector, a connecting rack for interchangeably connecting said sources of signaling current and the bank signaling contacts, a connection extending from the signaling wiper to a line wiper for conducting signaling current from the selected bank signaling contact to said line wiper, interrupter means included in the signaling current path for controlling the application of signaling current in successive trains of series, and means controlled by the said interrupter whereby the application of any portion of a train of series will be disabled from being initially applied after the interrupter has started the application of a train.

15. In a telephone system, a connector switch, line bank contacts for the connector, signaling contacts for the connector bank corresponding to the line contacts, a plurality of sources of different signaling currents, line and signaling wipers for the connector, a connecting rack for interchangeably connecting said sources of signaling current and the bank signaling contacts, a connection extending from the signaling wiper to the line wiper for conducting signaling current from the selected bank signaling contact to said line wiper, interrupter means included in the signaling current path for controlling the application of signaling current in successive trains of series, means controlled by the said interrupter whereby the application of any portion of a said train of series will be dis-

abled from being initially applied after the interrupter has started the application of a train, telephone lines, and a second connecting rack for interchangeably connecting said lines and line contacts.

16. In a telephone system, a connector switch, line bank contacts for the connector, signaling contacts for the connector bank corresponding to the line contacts, a plurality of sources of different signaling currents, line and signaling wipers for the connector, a connecting rack for interchangeably connecting said sources of signaling current and the bank signaling contacts, a connection extending from the signaling wiper to a line wiper for conducting signaling current from the selected bank signaling contact to said line wiper, interrupter means included in the signaling current path for controlling the application of signaling current in series constituting alternate live and dead periods, and means controlled by the said interrupter whereby the application of a said series will be disabled from being initially applied after the interrupter has started the application of a live period.

17. In a telephone system, a connector switch, line bank contacts for the connector, signaling contacts for the connector bank corresponding to the line contacts, a plurality of sources of different signaling currents, line and signaling wipers for the connector, a connecting rack for interchangeably connecting said sources of signaling current and the bank signaling contacts, a connection extending from the signaling wiper to a line wiper for conducting signaling current from the selected bank signaling contact to said line wiper, interrupter means included in the signaling current path for controlling the application of signaling current in series constituting alternate live and dead periods, means controlled by the said interrupter whereby the application of a said series will be disabled from being initially applied after the interrupter has started the application of a live period, telephone lines, and a second connecting rack for interchangeably connecting said lines and line contacts.

18. In an automatic telephone system, an automatic connector switch, a called line, a current interrupter means included in a signaling current path of the connector for controlling the application of signaling current from the connector to the connected called line in successive trains of series, automatically applied means made operative solely responsive to effecting the connection to the called line for causing said application of signaling current to be initiated, and means controlled by the said interrupter whereby the application of any portion of a said train of series will be disabled from being initially applied through the connector after the interrupter has started the application of a train

but will be enabled to apply the next succeeding train thereafter.

19. In a telephone system, a connector, a called line accessible from the connector, signaling mechanism for applying signaling current to the called line in a series of alternate live and dead periods, and automatically applied means for causing the signaling current to be applied to the called line only at the starting of the next live period solely responsive to the operation of the connector in effecting connective relation with the called line regardless of the time said operation occurs.

20. In a telephone system, a connector, a called line accessible from the connector, code signaling mechanism for applying signaling current to the called line in a predetermined series of alternate live and dead periods, means for preventing the initial application of signaling current to the called line intermediate of a said series, and automatically applied means for causing the signaling current to be applied to the called line only at the starting of the first live period of the next series solely responsive to the operation of the connector in effecting connective relation with the called line regardless of the time said operation occurs.

21. In a telephone system, a connector, a called line accessible from the connector, code signaling mechanism for applying signaling current to the called line in a predetermined series of non-uniform alternate live and dead periods, means for preventing the initial application of signaling current to the called line intermediate of a said series, and automatically applied means for causing the signaling current to be applied to the called line only at the starting of the first live period of the next series solely responsive to the operation of the connector in effecting connective relation with the called line regardless of the time said operation occurs.

22. In a telephone system, a connector, a called party line, a plurality of branches of said line accessible from the connector, code signaling mechanism for applying signaling current from a specific source of any one of a plurality of different characters to the called line in a predetermined series of alternate live and dead periods, automatically applied means for causing the signaling current to be applied to the called line only at the starting of the first live period of the next series responsive to the operation of the connector in effecting connective relation with the called line regardless of the time said operation occurs, and automatically applied means for causing a specific said code series of specific said character of current to be applied to the called line in correspondence with the branch of the called line the connector is operated into connective relation with so that a different code series of signaling current of

a specific said character will be applied to the called line depending upon which branch of the called line is connected with.

23. In an automatic telephone system, a
5 connector, a called line accessible from the connector, a signaling current source for application to the called line from the connector, a relay operated for closing a circuit path between the signaling current source and the connector, and a conductor individual to the called line included in said circuit path between the source and the connector over which said relay is operatively energized.

10

which said connector is operatively energized.

15 24. In an automatic telephone system, a directly controlled connector, a called line accessible from the connector, a source of signaling current having intermittently live periods for application to the called line from the connector, a relay operated for closing a circuit path between the signaling current source and the connector included in said circuit path between the source and the connector over which said relay is operatively energized, and means the operation of which

20 25 is non-directively initiated after the connector has been operated into connection with the called line for causing the operation of the relay only at a predetermined time with respect to the live periods of the signaling

30 current source.

35 25. In an automatic telephone system, a connector, a called line accessible from the connector, a signaling current source specific to the called line for application to the called line from the connector, a relay operated for closing a circuit path between the signaling current source and the connector including a wiper of the connector and a terminal of the called line, and a conductor individual to the called line included in said circuit path between the source and the connector over which said relay is operatively energized.

26. In an automatic telephone system, a connector, a plurality of called lines accessible from the connector, signaling current sources specific to the respective called lines for application to the line called from the connector, a relay operated for closing a circuit path between the signaling current source and the connector including a wiper of the connector and a terminal of the selected called line, and a conductor individual to the called line included in said circuit path between the source and the connector over which said relay is operatively energized.

27. In an automatic telephone system, a directly controlled connector, a plurality of called lines accessible from the connector, sources of signaling current specific to the respective called lines having intermittent live periods for application to the line called from the connector, a relay operated for closing a circuit path between the signaling current source and the connector including a wiper of the connector and a non-talking ter-

75
28. In an automatic telephone system, a connector, a plurality of called lines accessible from the connector, a source of signaling current and terminal therefor specific to each said line, a wiper of the connector cooperative with the respective said terminals when a line companion thereto is connected to by the connector, a relay operative to complete a circuit path from the signaling current terminal of the connected line to its companion line, and means controlled over the signaling current terminal of the connected line to operate the relay. 20
25

29. In an automatic telephone system, a connector, a plurality of called lines accessible from the connector, a source of signaling current having intermittent live periods and terminal therefor specific to each said line, a wiper of the connector cooperative with the respective said terminals when a line companion thereto is connected to by the connector, a relay operative to complete a circuit path from the signaling current terminal of the connected line to its companion line, and means controlled over the signaling current terminal of the connected line to operate the relay only at a predetermined time with respect to a live period of the corresponding signaling current source.

30. In an automatic telephone system, a connector, a plurality of called lines accessible from the connector, a source of signaling current and terminal therefor specific to each said line, a wiper of the connector co-operative with the respective said terminals when a line companion thereto is connected to by the connector, a relay operative to complete a circuit path from the signaling current terminal of the connected line to its companion line, and non-directive means applied over the signaling current terminal of the connected line for causing the operation of the relay responsive to effecting connection to the line called. 103 110 115

31. In an automatic telephone system, a connector, a plurality of called lines accessible from the connector, a source of signaling current having intermittent live periods and terminal therefor specific to each said line, a wiper of the connector cooperative with the respective said terminals when a line companion thereto is connected to by the connector, a relay operative to complete a circuit path from the signaling current terminal of the connected line to its companion line, and

non-directive means applied over the signaling current terminal of the connected line for causing the operation of the relay responsive to effecting connection with the line called but only at a predetermined time with respect to a live period of the corresponding signaling current source.

32. In an automatic telephone system, a connector, a plurality of lines accessible from the connector, a source of signaling current, a busy-test terminal for each line, a terminal specific to each line for controlling the application of signaling current to its companion line in a specific manner, a wiper of the connector cooperative with the respective said specific terminals when a random said line companion thereto is connected to by the connector, relay mechanism operative to prepare a signaling current path to the connected line, and means controlled over said specific terminal of the connected line to operate the relay mechanism to apply said signaling current over said specific terminal to a talking conductor of the called line.

33. In an automatic telephone system, a connector, a plurality of lines accessible from the connector, a source of signaling current having intermittent live periods and a terminal therefor specific to each said line for controlling the application of signaling current to its companion line in a specific manner, a wiper of the connector cooperative with the respective said terminals when a random said line companion thereto is connected to by the connector, relay mechanism operative to prepare a signal circuit path to the connected line, and means controlled over the said specific terminal of the connected line to operate the relay mechanism only at a predetermined time with correspondence to the requirement of said specific manner to apply said signaling current over said specific terminal to a talking conductor of the called line.

34. In a telephone system, a connector, a plurality of lines accessible from the connector, a differently selectively responsive signal device on the respective said lines, a signaling current source specific to each said device, a relay, a wiper of the connector, an auxiliary terminal of the respective said lines cooperative with the wiper when a line is connected to by the connector, means whereby the operation of the relay will be controlled over the wiper responsive to a random said line being selected, and means for causing the relay by its said operation to apply signaling current over the said auxiliary terminal of the selected line to the selected line from the source having the character specific to the selected line.

35. In a telephone system a connector, a branched line, each said branch accessible from the connector over specific bank terminals therefor, differently selectively re-

sponsive signal devices on the line each specific to a said branch, signaling current sources having characters specific to the respective branches, a relay, a wiper of the connector, an auxiliary terminal of the respective branches cooperative with the wiper when a random said branch is selected by the connector, means whereby the operation of the relay will be controlled over the wiper responsive to a said branch being selected, and means for causing the relay by its said operation to apply signaling current over the said auxiliary terminal of the selected line to the selected line from the source having the character specific to the branch selected to operate only the corresponding signal device on the line.

36. In a telephone system, a connector, a plurality of lines accessible from the connector, a differently selectively responsive signal device on the respective lines, a source of periodically live signaling current specific to each said device, relay mechanism, a wiper of the connector, an auxiliary terminal of the respective lines cooperative with the wiper when a said line is connected to by the connector, means whereby the operation of the relay mechanism will be controlled over the wiper responsive to a random said line being selected, means for causing the relay mechanism by its said operation to apply signaling current from the source having the character specific to the line selected to said line wherein said wiper forms a path for the signaling current, and means non-directively applied for causing the signaling current to be applied to the selected line only at a predetermined time with respect to the live periods thereof.

37. In a telephone system, a connector, a plurality of line branches accessible from the connector, line signal devices corresponding to the branches, sources of differently periodically live signaling current commonly effective to said devices but specific to the respective said branches, relay mechanism, a wiper of the connector, an auxiliary terminal of the respective said branches cooperative with the wiper when a said branch is connected to by the connector, means whereby the operation of the relay mechanism will be controlled over the wiper responsive to a random said branch being selected, means for causing the relay mechanism by its said operation to apply signaling current from the source specific to the branch selected to its line to commonly operate the signal devices thereon wherein said wiper forms a path for the signaling current, and means non-directively applied for causing the signaling current source corresponding to the branch selected to be applied to the line only at a predetermined time with respect to the live periods of said signaling current source.

38. In a telephone system, a connector, a called line accessible from said connector over any one of a plurality of branches of the line, a signal device on said line corresponding to each said branch, a code current sending device corresponding to each said branch for supplying signaling current in a train of successive live and dead periods for application to the called line over the branch selected by the connector, means for preventing application of signaling current to the called line except at the beginning of a code, means whereby the starting of the application of a code to the called line will be independent of the time of effective operation of any said code sending device other than the one corresponding to the branch selected regardless of when the branch of the line is selected, and means whereby the branch of the line selected will determine the corresponding code current sending device and cause the corresponding signaling code to be applied to the corresponding signal device to operate it with specific correspondence to the branch selected.

39. In a telephone system, a connector, a called line accessible from the connector over any one of a plurality of branches of the line, a signal device on said line corresponding to each said branch, a current source corresponding to each branch for supplying signaling current for application to the called line in successive live and dead periods over the branch selected by the connector, means for preventing application of signaling current to the called line except at the beginning of a live period, means whereby the application of current to the called line will be independent of time of effective operation of any said sending device other than the one corresponding to the branch selected regardless of when the branch of the line is selected, means whereby the branch of the line selected will determine the signal device to be operated by the signaling current by also thereby selecting the corresponding current source and for causing the selected source to be applied operatively effective to only the corresponding signaling device.

40. In a telephone system, a connector, a plurality of called lines accessible from said connector, a source of current specific to each said line, means for operating said connector to select a desired one of said lines, means for applying said sources of current in successive live and dead periods, means whereby the current will be applied to a called line from the connector only at the inception of a live period, means whereby regardless of the time the connector selects a called line the application of the current thereto from the specific source will be irrespective of the time of effecting live and dead periods of other said sources, and means whereby the specific said source will be applied to the

called line in correspondence with the line called responsive to the selection of the called line.

41. In a telephone system, a connector, a plurality of called line branches accessible from said connector, a current supply branch specific to each said line branch, means for operating said connector to select a desired one of said line branches, means specific to each said line branches for applying said currents in successive live and dead periods, means whereby the current will be applied to a called line branch from the connector only at the inception of a live period, means whereby regardless of the time the connector selects a line branch the application of the current thereto from its corresponding supply branch will be irrespective of the operative position then assumed by said means for applying current over any of said supply branches other than the one of said means corresponding to the branch selected by the connector, and means whereby the specific said supply branch will be applied to the called line in correspondence with the line branch called.

In witness whereof, I hereunto subscribe my name this sixteenth day of June, 1923.

HERBERT M. FRIENDLY.
